H. MELTZER

CLASP DEVICE

Filed May 12, 1923

Inventor
Hyman Meltzer
By his Attorneys
Edgar Tate & Co

UNITED STATES PATENT OFFICE.

HYMAN MELTZER, OF BROOKLYN, NEW YORK.

CLASP DEVICE.

Application filed May 12, 1923. Serial No. 638,466.

To all whom it may concern:

Be it known that I, HYMAN MELTZER, a citizen of the United States, and residing at Brooklyn, in the county of Kings and State of New York, have invented certain new and useful Improvements in Clasp Devices, of which the following is a specification, such as will enable those skilled in the art to which it appertains to make and 10 use the same.

This invention relates to clasp devices and particularly to devices of this class designed for use in connection with vanity cases, small handbags, suitcases and the like; 15 and the object of the invention is to provide a device of this class composed of separate parts fashioned from sheet metal or from suitably formed sheet metal blanks; a further object of the invention being to 20 provide improved means for retaining the yoke or lock member of devices of this class in connection with one part thereof and for reinforcing that part of the clasp device in connection with which said yoke or lock 25 member is mounted, a still further object being to provide the crosshead of the yoke or lock member with means cooperating with a flat spring for retaining said member under tension in its operative position; 30 and with these and other objects in view, the invention consists in a clasp device of the class and for the purpose specified which is simple in construction and efficient in use; and which is constructed as hereinafter 35 described and claimed and produced in accordance with the method hereinafter set out.

The invention is fully disclosed in the following specification, of which the accompanying drawing forms a part, in which the separate parts of my improvement are designated by suitable reference characters in each of the views, and in which:—

Fig. 1 is a bottom plan view of my complete clasp device, detached.

Fig. 2 is a partial section on the line 2—2 of Fig. 1.

Fig. 3 is a view similar to Fig. 2 but showing the yoke or lock member in a different position.

Fig. 4 is a blank from which one part of my improved clasp device is made.

Fig. 5 is a sectional view of the clasp device showing the first step in the process of forming the same.

Fig. 6 is a blank from which the yoke or lock member is formed.

Fig. 7 is a blank from which the other part of the clasp device is made.

Fig. 8 is a perspective detail view of that 60 part of the clasp device which is made from the blank shown in Fig. 7; and,

Fig. 9 is a plan view of the sheet metal spring which I employ.

My improved clasp device comprises two 65 body portions 10 and 11, and for the purpose of description, the body portion 10 will be regarded as the main body portion and 11 the supplemental body portion. I also employ a yoke or lock member 12 and 70 a sheet metal spring 13. In Fig. 4 of the drawing, I have shown a blank 10^a from which the main body portion 10 is formed and this blank is of an irregular contour but one end is substantially semi-circular 75 in form as shown at 14 and provided with three equally spaced projecting fingers 15. The other end portion of the blank is mounted as shown at 16 and provided at one side thereof with projecting curved fingers 17 having square shoulder portions 18 and at the opposite side are arc-shaped recesses 19. In forming the main body portion 10, the blank 10^a is formed from suitable dies and fashioned into the form shown 80 in Fig. 5 of the drawing, or in other words, to form a cup-shaped body 20, which is arc-shaped in form at one end as shown at 21 in Fig. 1 of the drawing, and the other end portion of which is reduced to form a 85 projecting arc-shaped nose 22, and the fingers 15 extend at right angles to the top face 23 of the body portion 10 as do also the fingers 17 as shown in Fig. 5. The arc-shaped nose 22 is hollow on its inner face 90 or provided with a recess 24.

The supplemental body portion 11 is formed from a blank 11^a shown in Fig. 7 of the drawing, and this blank is substantially semi-circular in form and provided 100 with three equally spaced fingers 25, and in forming the body portion 11, the blank 11^a is fashioned into the form shown in Fig. 8 of the drawing to form a substantially arc-shaped semi-circular body portion, and the straight wall 26 thereof is apertured as shown at 27 to receive the projecting nose 22 of the main body portion 10 as clearly shown in Figs. 1 to 3, inclusive, 105 and the fingers 25 extend at right angles 110

to the top face 28 of the body portion 11 as clearly shown in Fig. 8.

The member 12 is blanked from sheet metal into the form shown in Fig. 6 of the drawing, and the member 12 is in the form of a loop or yoke, arc-shaped in form at one end as shown at 29 and provided with a slight projecting portion 30 and the other end of which is connected by a transverse crosshead 31 having an enlarged central portion 32, which projects at the opposite sides of the crosshead 31 as shown at 33 and 34. In completing the part 12 the crosshead portion thereof is bent at a slight angle to the plane of said member as clearly shown in Figs. 2 and 3 of the drawing.

The spring part 13 is composed of a strip of spring metal, one end portion of which is rounded as shown at 35 to conform with the curvature of the main body portion 10 or the recess therein, and the other end portion of said spring part is reduced to form a projecting and rounded nose 36, which fits within the recess 24 of the nose 22.

In assembling the several parts of my improved clasp device, after said parts have been fashioned in the manner above set out, the spring part 13 is first placed within the main body portion 10 as shown in Figs. 1 to 3 inclusive, after which the member 12 or the crosshead portion 31 thereof is placed within the recesses 19 at the opposite sides of the body portion 10, and the projecting curved fingers 17 are then folded inwardly over and partially around the crosshead portion 31 of the member 12 as shown at 37 in Figs. 1 to 3 inclusive, to retain the member 12 against displacement from the main body portion 10 and also to hold said member in proper position in the recesses 19, and yet permit of the rotation or swinging movement of the member 12 in the body portion 10.

It will be noted that when the supplemental body portion 11 is mounted in connection with the main body portion 10 or when the nose 22 passes into the aperture 27 of the body portion 11 as shown in Figs. 1 to 3 inclusive, and the member 12 is moved into its closed and operative position as shown in Figs. 1 and 2, that said member is held firmly upon the body portion 11 under the tension of the spring 13, said spring comprising upwardly arranged projections 33 at one side of the enlargement 32 of the crosshead 31 as clearly shown in Fig. 2 of the drawing, and when the body portion 11 is removed, the yoke or lock member 12 will assume a position at a slight angle to that shown in Fig. 2, in which position the face of the enlargement 32 will lie flat upon the spring 13. The member 12 may also be tensionally held in the position shown in Fig. 3 or may be swung backwardly to lie upon the top face of the main body portion 10 if

desired, when the parts of the clasp device are in an inoperative position.

The above described means of retaining the member 12 in its operative position under tension is one of the distinctive features of the present invention together with the specific manner in which the member 12 is retained and supported in connection with the main body portion 10, and while I have shown certain details of construction for carrying my invention into effect and have shown a specific method of forming the separate parts of my improved clasp device, it will be understood that I am not necessarily limited in these respects and various changes in and modifications of the construction herein shown and described may be made within the scope of the appended claims without departing from the spirit of my invention or sacrificing its advantages.

Having fully described my invention, what I claim as new and desire to secure by Letters Patent, is:—

1. In a clasp device of the class described, a main body portion composed of sheet metal, a lock member mounted in recesses at the opposite sides of said body portion and provided with a cross-head extending transversely of and through said body portion and said body portion being provided with projecting fingers adapted to be folded inwardly and around the crosshead of said lock member for retaining said lock member against displacement from said body portion, and other projecting fingers on said body portion for mounting the same in connection with a suitable support.

2. In a clasp device of the class described, a main cup-shaped body portion fashioned from sheet metal, a lock member mounted in recesses at the opposite sides of said body portion and provided with a crosshead extending transversely of said body portion, means at the opposite sides of said body portion adapted to be folded inwardly around the crosshead of said lock member for retaining said member in connection with said body portion, and a sheet metal spring mounted in the body portion and cooperating with said lock member to control the operation thereof, and a plurality of projecting members on said body portion by means of which the same may be secured to a predetermined support.

3. A clasp device of the class described comprising a main cup-shaped body portion fashioned from sheet metal, a lock member mounted in recesses at the opposite sides of said body portion and provided with a cross-head extending transversely of said body portion, means at the opposite sides of said body portion adapted to be folded inwardly around the crosshead of said lock member for retaining said member in connection with said body portion, a sheet metal spring

mounted in the body portion and cooperating with said lock member to control the operation thereof, the crosshead of said lock member being provided centrally thereof with an enlarged portion, which cooperates with said spring to retain said lock member in its operative position under tension, a supplemental sheet metal body portion adapted to interlock with said main body portion and in connection with which said lock member cooperates, and said main and supplemental body portions being provided with projecting fingers.

4. A clasp device of the class described comprising main and supplemental body portions composed of sheet metal, said body portions being adapted to interlock one with the other, a lock member retained in connection with said main body portion and cooperating with said supplemental body portion to retain said body portions in connection with each other, means in the main body portion and cooperating with said member for holding the same in its operative position under tension, the side walls of said

main body portion being provided with curved fingers adapted to be folded around said lock member to retain the same in connection with the main body portion, and said main and supplemental body portions being provided with a plurality of projecting fingers for securing the same to predetermined supports.

5. In a clasp device of the class described a substantially cup-shaped body portion, the opposite side walls of which are provided with recesses, a substantially loop-shaped lock member having a crosshead portion adapted to enter the recesses of said body portion, and the walls of said body portion being provided with a plurality of projecting members, two of which are curved and adapted to be folded around the crosshead portion of said lock member to retain the same in engagement with said body portion.

In testimony that I claim the foregoing as my invention I have signed my name this 9th day of May, 1923.

HYMAN MELTZER.
